ATTORNEY

UNITED STATES PATENT OFFICE.

TOM M. ANDERSON, JR., OF KNOXVILLE, TENNESSEE, ASSIGNOR OF ONE-THIRD TO
GEORGE W. MAYER, OF HARRIMAN, TENNESSEE.

LOCK.

1,254,960.

Specification of Letters Patent. Patented Jan. 29, 1918.

Application filed June 20, 1917. Serial No. 175,898.

To all whom it may concern:

Be it known that I, TOM M. ANDERSON, Jr., a citizen of the United States, residing at Knoxville, in the county of Knox and 5 State of Tennessee, have invented new and useful Improvements in Locks, of which the following is a specification.

This invention relates to locks and more particularly to a screen door lock and hook 10 which is so constructed that young children will not be able to unlock the door.

Another object of the invention resides in the provision of a simple and practical screen door lock having a sliding spring 15 pressed bolt to engage lockingly with a hook mounted on the door, said bolt being easily releasable from the hook when free to slide.

The invention also aims to generally improve fasteners of this nature to render 20 them more practical, reliable and commercially desirable.

With these and other objects in view as will become more apparent as the description proceeds, the invention consists in certain 25 novel features of construction, combination and arrangement of parts as will be hereinafter fully described, illustrated and claimed.

In the drawing, 30 Figure 1 is a view showing the lock co-acting with a screen door.

Fig. 2 is a sectional view through the device between the sides thereof showing the lock mechanism.

35 Fig. 3 is a sectional view on the plane of line 3—3 of Fig. 1, and

Fig. 4 is a detail perspective view of the keeper.

Referring in detail to the drawings by 40 numerals, 1 designates a door casing, and 2 a screen door. While I have shown my locking means applied to a screen door, it will be understood that I do not wish to be limited to this application but may use the 45 device for securing other movable members. The lock 3 comprises a casing which is secured in position by attaching arms 4. Within the casing is mounted a sliding bolt 5 which extends outwardly through the side edge wall 6 of the casing through the opening 7 therein. The bolt is formed with a longitudinal slot 8 through which extends a stud 9 on which the bolt slides. The slotted head portion of the bolt is somewhat larger 55 than the remaining shank portions and

forms abutments for the expansive helical spring 10 which encircles the shank. The inner end of the bolt is formed with a nose or catch 11 which slides under and across the hook opening 12 in the top wall 13 of the casing. The upper edge 14 of the nose or catch is inclined as shown.

An arm 15 is formed integrally with the head of the bolt, depends therefrom and has a lateral extension 16 at its lower end, 65 which extension is adapted to be engaged by the bill 17 of a revoluble dog 18 having a hub 19 formed with a square key opening 20. The dog is revolvably mounted between the side walls of the casing, which side walls 70 have openings registering with the opening 20. The hub extends into the opening in the rear side wall 21 of the casing whereas the front side wall or cover wall 22 is dished inwardly around the opening to fit into the 75 concave side of the keeper and to furthermore provide a guide to the key hole.

A dislodging pin 23 extends slidably through openings in the top wall 13 and bottom wall 24 of the casing and is held 80 normally in an elevated position by the spring 25.

The swinging door carries a hook or hasp 26 having a slotted tongue 27 and a finger hold 28. The hasp or hook may be secured 85 to the door by any suitable means such as the screw eye 29 which permits the hook to swing.

The hook may be secured to the lock by simply inserting its slotted tongue into the 90 opening 12, which movement will cause the bolt to first retract and then snap into the slot in the tongue. When the hook is positioned to engage the bolt, the dislodging pin 23 is depressed. Now to disengage the hook, simply pull on the protruding portion of the 95 bolt shank to remove the nose or spur 11 from the slot in the tongue whereupon the dislodging pin will force the tongue out of the lock casing. The dog 18 may be turned 100 by the key 30 to engage the arm 15 and hold the bolt against retraction.

While I have shown and described the preferred embodiments of my invention, it will be clearly understood that I do not wish 105 to be limited to this construction, but may make such changes as will fall within the scope and spirit of the invention as claimed.

What I claim is:—

1. The combination in a lock of a casing 110

formed in one side with a slot, said casing further formed with an opening spaced apart from said slot, a spring-pressed bolt slidably mounted in said casing, said bolt 5 having a nose normally extending across said slot, a spring-pressed dislodging pin mounted within the casing and having one end projecting outwardly through said opening, and a hook adapted to be secured to a 10 movable member, said hook having a tongue adapted for entering said slot and engaging with the nose of said bolt, said hook further having a portion adjacent said tongue adapted to engage against said dislodging pin, 15 whereby said hook will be entirely displaced from said slot when disengaged from said bolt.

2. The combination in a lock of a casing formed in one side with a slot, said casing 20 further formed with an opening spaced

apart from said slot, a shank on the bolt extending outwardly through said casing whereby the bolt may be manually actuated, a spring-pressed bolt slidably mounted in said casing, said bolt having a nose normally 25 extending across said slot, a spring-pressed dislodging pin mounted within the casing and having one end projecting outwardly through said opening, and a hook adapted to be secured to a movable member, said hook having a tongue adapted for entering said slot and engaging with the nose of said bolt, said hook further having a portion adjacent 30 said tongue adapted to engage against said dislodging pin, whereby said hook will be 35 entirely displaced from said slot when disengaged from said bolt.

In testimony whereof I affix my signature.

TOM M. ANDERSON, JR.
